UNITED STATES PATENT OFFICE.

HERBERT A. WALLACE, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed May 16, 1923. Serial No. 639,815.

To all whom it may concern:

Be it known that I, HERBERT A. WALLACE, a citizen of the United States, residing at Edgewood Borough, in the county of Allegheny and State of Pennsylvania, have invented certain new and useful Improvements in Railway-Traffic-Controlling Apparatus, of which the following is a specification.

- 10 My invention relates to railway traffic controlling apparatus, and particularly to apparatus of the type comprising train carried governing means controlled in part by energy received from the trackway.
- 15 More particularly my invention relates to the trackway portion of such apparatus.

I will describe two forms of railway traffic controlling apparatus embodying my invention, and will then point out the novel features thereof in claims.

In the accompanying drawings, Fig. 1 is a diagrammatic view showing one form of railway traffic controlling apparatus embodying my invention. Fig. 2 is a view 25 showing a modification of the apparatus shown in Fig. 1 and also embodying my invention.

Similar reference characters refer to similar parts in each of the views.

30 Referring first to Fig. 1, the reference character 1 designates the track rails of a railway over which traffic normally moves in the direction indicated by the arrow. These track rails are divided by means of 35 insulating joints 2 into a plurality of insulated track sections of which only one section A—B is shown in the drawing. As here shown each of said track sections constitutes a block. This section is provided 40 with a source of track circuit current which comprises as shown in the drawing, a secondary winding 9 of a track transformer T connected across the rails adjacent the exit end of the section. The primary winding 45 10 of this track transformer T is constantly supplied with alternating current through wires 25 and 26 from line wires 6 fed by an alternator G. Interposed between 50 secondary 9 of each track transformer and one rail of the associated section is an impedance 9^a one function of which is to limit the output of the track transformer when its terminals are short-circuited by the wheels and axles of a train. Section A—B

is also provided with a track relay R^A 55 which is connected across the rails adjacent the entrance end of the section. It is therefore clear that track section A—B is provided with a track circuit comprising secondary winding 9 of track transformer T, 60 the track rails 1 of the section and track relay R^A.

Means are also provided for supplying to the rails of the section an alternating current which I will hereinafter term a "local" current. As here shown, this current is supplied to the two track rails in parallel. The immediate source of this current is secondary winding 7 of a local transformer D whose primary winding 8 is constantly supplied with alternating current from line wires 6. An impedance 3 is connected across the rails adjacent the entrance end of the section, a similar impedance 5 is connected across the rails adjacent the exit 75 end of the section, and a third similar impedance 4 is connected across the rails at some intermediate point in the section. The supply of local current to the rails of the section is controlled by traffic conditions in advance of the section, and as here shown it is controlled by track relay R^B for the section in advance of section A—B. One local circuit passes from the right hand terminal of secondary winding 7 of local 80 transformer D, through wires 19 and 21, front contact 11—14 of relay R^B, wire 22, to the mid-point of impedance 5, thence through the rails of section A—B to impedance 3, wire 24, front contact 13—16 of relay R^B, and wire 18 back to the left hand terminal of secondary winding 7. This circuit is closed only when relay R^B is energized, under which condition current of what I will term "normal" relative polarity is supplied to the rails of section A—B from end to end. Another circuit is provided which passes from the right hand terminal of secondary 7 through wires 19 and 20, back contact 13—17 of relay R^B, wire 90 24, to the mid-point of impedance 3, thence through the rails in parallel of section A—B to impedance 4, thence through wire 23, back contact 12—15 of relay R^B, and wire 18, back to the left hand terminal of secondary winding 7. This circuit is closed only when relay R^B is deenergized, under which conditions current of what I shall

term "reverse" relative polarity is supplied to the rails of section A—B between impedances 3 and 4.

It will thus be seen that the relay contacts 11, 12, and 13, constitute a pole changer for supplying local current of one relative polarity from secondary 7 to the rails of section A—B throughout the entire length of the section, or local current of the other relative polarity from the same secondary 7 to the rails of section A—B from the entrance end 3 to the intermediate point 4 in the section.

It is understood that while only one of the track sections of the railway is shown in the drawing a plurality of successive sections will ordinarily be equipped with apparatus similar to that shown for section A—B.

Before explaining the operation of the apparatus it should be pointed out that the trackway apparatus here shown is intended for cooperation with train carried governing apparatus which operates in the following manner: When the train occupies a section of track which is supplied with track circuit current and also with local current of normal relative polarity the governing apparatus gives a proceed indication. When the train is on a portion of track which is supplied with track circuit current and with local current of reverse relative polarity the governing apparatus gives a caution indication. When the train is on a portion of track from which the supply of either local current or track circuit current is interrupted, the governing apparatus gives a stop, or slow, indication.

As shown in the drawing, the parts are in normal position, that is, the positions corresponding to an unoccupied condition of section A—B and the next section in advance. I will now assume that a train traveling in the direction of the arrow enters section A—B. The train will receive a proceed indication through section A—B since it is supplied with track circuit current and local current of normal relative polarity. As this train enters the track section to the right of point B, track relay R^B will become de-energized, thus reversing the local current between impedances 3 and 4, and discontinuing the local current between impedances 4 and 5 in section A—B. While such train occupies the section to the right of point B, a following train entering section A—B will accordingly receive a caution indication between impedances 3 and 4, and a stop or slow indication between impedances 4 and 5.

In Fig. 2 each section is provided with a signal designated by the reference character S with an exponent corresponding to the location, each of which signals is, as here shown, of the three-position semaphore type

adapted to indicate "proceed", "caution" or "stop". Each signal is controlled, by means not shown in the drawing but including the associated track relay, in such a manner that when the corresponding section is occupied the signal indicates "stop", when the corresponding section is unoccupied and the section next in advance is occupied, the signal indicates "caution", and when the corresponding section and the section next in advance are both unoccupied, the signal indicates "proceed". In this view all the rest of the apparatus is the same as that shown in Fig. 1 except that the local circuits for section A—B are controlled by means of a circuit controller P^B operated by signal S^B for the section in advance of B. When signal S^B is at proceed or caution the circuit controller P^B occupies the position shown in the drawing and local current then flows from secondary 7 of transformer D, through wire 19, circuit controller P^B, wire 22, impedance 5 in section A—B, through the rails of the section in parallel to impedance 3, wire 24, circuit controller P^B, and wire 18 back to secondary 7 of transformer D, under which conditions section A—B is supplied with local current of normal relative polarity throughout the length of the section. If, however, signal S^B is at stop, circuit controller P^B is reversed, and local current then flows from secondary 7 of local transformer D, through wire 19, circuit controller P^B, wire 24, impedance 3 in section A—B, through the rails of the section in parallel to impedance 4, wire 23, circuit controller P^B, and wire 18, back to secondary 7 of transformer D. When this circuit is closed section A—B is supplied with local current of reverse relative polarity between impedances 3 and 4 but with no local current between impedances 4 and 5.

It will thus be seen that the circuit controller P^B constitutes a pole changer for supplying local current of one relative polarity from secondary 7 to the rails of the section A—B throughout the entire length of the section or local current of the other relative polarity from the same secondary 7 to the rails of section A—B between impedances 3 and 4.

A train passing through the stretch of track shown in the drawing operates the apparatus exactly as described in connection with Fig. 1 and the functioning of the apparatus will be clear without further explanation.

One feature of my invention is the provision of means for supplying local current to each section from a single source of energy located at one end of the section and controlled by a simple arrangement of contacts responsive to traffic conditions in advance of the section.

Although I have herein shown and de-

scribed only two forms of railway traffic controlling apparatus embodying my invention, it is understood that various changes and modifications may be made therein within the scope of the appended claims without departing from the spirit and scope of my invention.

Having thus described my invention what I claim is:

- 5 1. In combination, a section of railway track, an impedance connected across the rails adjacent one end of said section, a second impedance connected across the rails adjacent the other end of said section, a third impedance connected across the rails at an intermediate point in said section, a source of energy, a normally closed contact for connecting said first impedance with one terminal of said source, a normally closed contact 10 for connecting said second impedance with the second terminal of said source, a normally open contact for connecting said second impedance with the said first terminal, a normally open contact for connecting said 15 third impedance with the said second terminal, and a track relay connected with the rails of the section next in advance and including said contacts.
- 20 2. In combination, a first and a second section of railway track, a track relay for said first section, and means controlled solely by said relay for supplying said second section with local current of one relative polarity throughout the length of the section, or with local current of the other relative polarity 25 through a portion only of the section from a single energy source.
- 30 3. In combination, a section of railway track, a source of local train governing current for said section, and a single pole

changer controlled by traffic conditions in advance of said section for supplying local current of one relative polarity from said source to the rails of the section throughout the length of the section or for supplying local current of the other relative polarity from said source to the rails of the section through a portion of the section.

4. In combination, a section of railway track, a source of local train governing current for said section, and a single pole changer controlled by traffic conditions in advance of said section for supplying local current of one relative polarity from said source to the rails of the section throughout the length of the section or for supplying local current of the other relative polarity from said source to the rails of the section from the entrance end of the section to an intermediate point in the section.

5. In combination, a section of railway track, an impedance connected across the rails adjacent one end of said section, a second impedance connected across the rails adjacent the other end of said section, a third impedance connected across the rails at an intermediate point in said section, a source of energy, a normally closed contact for connecting said first impedance with one terminal of said source, a normally closed contact for connecting said second impedance with the second terminal of said source, a normally open contact for connecting said second impedance with the said first terminal, a normally open contact for connecting said third impedance with the said second terminal, and a signal for the section next in advance for controlling said contacts.

In testimony whereof I affix my signature.
HERBERT A. WALLACE.
